CLAIM

The ornamental design for a beer tap handle, as shown and described.

DESCRIPTION

FIG. 1 is a front upper perspective view of the beer tap handle of the present invention;

FIG. 2 is a front elevational view of the beer tap handle of the present invention shown in FIG. 1;

FIG. 3 is a back elevational view of the beer tap handle of the present invention shown in FIG. 1;

FIG. 4 is a left side elevational view of the beer tap handle of the present invention shown in FIG. 1;

FIG. 5 is a right side elevational view of the beer tap handle of the present invention shown in FIG. 1;

FIG. 6 is a top plan view of the beer tap handle of the present invention shown in FIG. 1;

FIG. 7 is a bottom plan view of the beer tap handle of the present invention shown in FIG. 1; The portions of the beer tap handle shown in broken lines in FIG. 7 form no part of the claimed design; and,

FIG. 8 is a back lower perspective view of the beer tap handle of the present invention shown in FIG. 1.
